CONTROL MECHANISM FOR TYPEWRITING MACHINES

Harry A. Foothorap, Harrisburg, Pa., assignor, by
mesne assignments, to Underwood Elliott
Fisher Company, New York, N. Y., a corpora-
tion of Delaware

Application July 24, 1930, Serial No. 470,519

23 Claims. (Cl. 197—2)

My invention relates to improvements in platen operating and control mechanism for typewriting machines of the class embodying a flat work clamping platen depressible from the writing plane to release the work, and printing mechanism movable over the work to line and letter space the printed record, and to a return position clear of the work.

In my U. S. Patent No. 1,904,127 dated April 10 18, 1933, there is disclosed an exemplification of this class of typewriting machine, to-wit, an Elliott-Fisher machine equipped with a motor drive to return the printing mechanism transversely of the machine to the left hand margin, or longitudinally of the machine to clear the work, as desired.

The principal object of my invention is to equip a machine of the above class so as to provide for the automatic depression of the platen, in timed relation to return movement of the printing mechanism to different positions, whereby movement of said mechanism, beyond that necessary to "clear" the work sheets or forms of different lengths, is obviated and operation of the machine expedited.

Another object of my invention is to provide platen depressing mechanism sufficiently reactive in character to yieldingly retain the platen in work-clamping position, but susceptible of operation to depress the same by application of a negligible amount of power, so that it may be operated either by a movable part of the machine, for instance, the printing mechanism, without imposing any appreciable extra load on said part, or, by a slight pressure of the hand upon a key lever.

To the accomplishment of the above and other objects subordinate thereto, and presently appearing, a preferred embodiment of my invention will now be described in detail, with reference to the accompanying drawings, and particularly defined in the claims appended hereto.

In said drawings,

Figure 1 is a top plan view illustrating my novel platen operating and control mechanism applied to an Elliott-Fisher machine of the type above mentioned.

Figure 2 is a rear elevation drawn on an enlarged scale, with parts of the printing mechanism eliminated for the sake of clearness,

Figure 3 is a fragmentary view in side elevation, parts showing in section,

Figure 4 is a longitudinal sectional view taken on the line 4—4 of Figure 1,

Figure 5 is a fragmentary view, similar to Figure 4, but drawn on an enlarged scale,

Figure 6 is a transverse sectional view taken on the line 6—6 of Figure 1,

Figure 7 is a similar view taken on the line 60 7—7 of Figure 1,

Figure 8 is a perspective view of a coupling device mounted on the line space carriage, a mounting and a latching mechanism included therein, and a platen-operating crank with which the coupling contacts, 5

Figure 9 is a vertical sectional view further illustrating the parts shown in Figure 8, and taken on the line 9—9 of Figure 2,

Figure 10 is a detail view partly in horizontal section and partly in top plan taken on the line 10 10—10 of Figure 9,

Figure 11 is a similar view taken on the line 11—11 of Figure 9,

Figure 12 is a detail view of a part of the latching mechanism, on the line 12—12 of Figure 9, 15

Figure 13 is a view partly in side elevation and partly in section, of one of a plurality of platen-moving toggles forming part of my platen operating mechanism, together with a ball bearing mounting therefor, 20

Figure 14 is a view in side elevation of one of said toggles and its mounting,

Figure 15 is a view in vertical section taken on the line 15—15 of Figure 14,

Figure 16 is a sectional view of a structural detail of one of said toggles, 25

Figure 17 is a view in side elevation of a portion of the control bail of the machine, and a motor control cam thereon adjustable to operative and inoperative positions, 30

Figure 18 is a vertical sectional view taken on the line 18—18 of Figure 17,

Figure 19 is a similar view illustrating a motor control cam adjusted into inoperative position,

Figure 20 is a fragmentary sectional view of a detail of the platen operating mechanism, and 35

Figure 21 is a longitudinal sectional view taken on the line 21—21 of Figure 8.

Referring to the drawings, and first to the general equipment of the Elliott-Fisher machine, I 40 (Figs. 1, 4 and 5) designates the usual track frame thereof formed by side members 2 and front, intermediate, and rear members 3, 3' and 3'', respectively. The flat platen 4, located within the frame 1, supports the work in a flat spread-out condition and in its normal elevated position, cooperates with overlying edge clamping bars 5, on the members 2, to clamp the work in position. The frame 1 is equipped with idler rolls 6 for facilitating the feeding of endless forms over the 50 platen 4, which need merely be identified in passing, since their function and operation is well understood in connection with these machines.

The printing mechanism, proper, which is of the usual type bar and key lever class, is supported by a printing head or carriage 7 mounted by rollers 8 upon the rails 11 and 12 of a line space carriage 9, for movement transversely of the platen to letter space the printed record. The printing head is propelled and controlled by 60

the usual typewriter appurtenances, such as the spring motor 10, and escapement mechanism, not shown.

The line space carriage 9, sometimes called the line space frame, but herein termed the carriage, and including the front and rear rails 11 and 12, respectively, and stretcher members 13 connecting the rails, is movable longitudinally of the platen 4 upon rollers 14 (Figs. 2 and 3), running on tracks 15 on the frame side members 2.

The line space carriage 9 is driven by a line space shaft 16 (Figure 2) journaled in said carriage and having fast thereon toothed pinions 17 meshing with racks 18 on the side members 2. Said shaft forms part of a line spacing mechanism, illustrated conveniently at 19, which, suffice it to say, operates said shaft in the proper direction to move the carriage 9 forwardly line space distances at a time. For details of this feature, reference may be had to my previously mentioned patent.

Referring to the motor drive, a motor 20 mounted upon the carriage 9 drives the line space shaft 16 through a motor control shaft 21, also mounted on the carriage, inter-meshing pinions 22 and 23 fast on the line space and motor control shafts, respectively, and forward and reverse driving clutches, not shown, in the housing 24. The motor control shaft 21 is endwise movable from a neutral position to engage either clutch so that the carriage is capable of motor operation forwardly, to quickly locate it over the work, or through a return excursion, to clear the work prior to removal of the same, or for other purposes, such as correction or proof reading.

Movement of the motor control shaft 21, in either direction, is effected by operation of a motor control bail 25 (Figures 1-3, 6 and 7) pivotally mounted, as at 26, on one frame member 2 to rock in opposite directions, respectively, and with which the motor control shaft 21 has a travelling connection in the form of a grooved wheel 27 (Figure 2) fast on said shaft and engaging the upper edge of said bail. The control bail 25 is rocked primarily, in the desired direction, by a pair of knee levers, one of which is shown at 28 (Figures 3-5) fast on individual shafts 29 (Figures 6 and 7) mounted in the frame 1 and suitably connected by linkage, indicated at 30, (Figure 4) with the bail 25. Stops 31 (Figures 5-7) on the shafts 29 limit movement of said shafts and bail.

At each end of the motor control bail 25, a cam 32 (Figures 1-3 and 6) is provided. As the carriage 9 nears the limit of either its forward or its return excursion, a lug 33 on the carriage engages the proper cam and rocks the bail to move the motor control shaft 21 to neutral position. For further details of the motor drive, reference may be had to my patent, previously mentioned.

In accordance with my invention, the platen 4 is anchored in a semi-floating condition within the frame 1 by a pair of subjacent platen guiding links 34 (Figures 4 and 5) extending longitudinally of the platen with their front ends pivoted at 35 adjacent the front member 3 of the frame and their rear ends pivoted at 36 to brackets 37 suitably secured to the under face of the platen.

Beneath the platen there is provided tensioned platen counter-balancing mechanism, including, preferably, a pair of opposed vertically movable bell crank levers 38 pivotally mounted at 39 on the front and intermediate members 3 and 3', respectively, of the frame along the longitudinal

median line of the platen 4, a retractile counterbalance spring 40 connecting the lower arms of said bell-crank levers 38, whereby the upper arms of the levers exert elevating counterbalancing forces in opposition to the weight of the platen 4.

In actual practice, the elevating forces exerted by the counterbalancing mechanism are, in the elevated position of the platen, less than that opposed thereagainst by the weight of the platen, but equal to said weight in the fully depressed position of said platen, and elevating forces sufficient to overcome the uncounterbalanced weight of the platen and sustain it in work-clamping position are supplied by the reactive platen operating mechanism now to be described.

Vertically disposed operating toggles 41 (Figures 4-6) are located beneath the platen 4 and roughly speaking, in proximity to the respective corners of the platen near the side edges thereof.

These platen-operating toggles are arranged, therefore, in pairs, one pair towards the front end of the platen and the remaining pair of toggles towards the rear end, thereof, and adapted for simultaneous operation to depress and to raise the platen, while maintaining it substantially level or horizontal.

The respective toggles 41 each comprise a link 44 and twin levers 42, the latter being fulcrumed intermediate their ends on hubs 43 (Figures 13-15) projecting inwardly from the inner faces 30 of the side frame members 2, which hubs are secured in place by suitable fastenings, as the screws 49 passing through the side frame members from the outer faces thereof.

The twin levers 42 are so fulcrumed on their hubs as to provide short upper arms 43a and longer lower arms 43b, the twin members of each lever being slightly spaced apart, in which position they are held by the headed bolts 52, passing through apertures in the outermost twin lever, 40 the threaded ends of the bolts engaging bushings 53 (Figure 16) screwed into the corresponding twin lever.

Ball bearings 47 occupy opposed races 48, 51, in the hub 43 and twin levers 42 respectively, 45 and relieve the friction at this point.

The upper end of the link 44 is pivotally connected to the lower face of the platen 4 at 45, the lower end of the link being embraced between and pivoted at 46 to the free ends of the 50 upper shorter arms 43a of the twin levers 43. The pivotal points 43, 45, and 46 lie in alinement when the toggle is straightened or extended to form a dead centre locking the platen in its raised or elevated position wherein it clamps the work 55 between its upper face and the edge-clamping bars 5.

Springs 54 connected to the respective joints 46 of their associated toggle levers 41 and to studs 55 on the frame 1 tend to straighten the 60 toggle levers and maintain them in such positions.

The provision of both counterbalancing means typified by the spring-pressed fingers 38, and the platen raising and lowering mechanism, typified by the toggle mechanisms 41, may require additional explanation.

The spring 40 (Figure 4) is of just sufficient strength to sustain the weight of the platen 4 in its elevated position, without material or substantial pressure against the ledges or paper edge clamping bars 5. In other words, the parts are in equilibrium.

The toggles 41 and their operating mechanism afford a means to positively raise and lower the 75

platen, and to press the platen with considerable force against the under surfaces of the paper edge clamping bars 5 to hold the work sheets in place.

5 Due to differences in temperature, and for other reasons, the platen is liable to warp and a strong pressure against the platen is required to flatten the latter to hold the edges of the platen firmly against the clamping bars throughout their length.

10 Therefore, to provide the considerable pressure necessary to clamp the work between the platen and the paper clamping bars 5, and to maintain the toggles in their straightened positions, the 15 toggle springs 54 must be very strong.

Given the above conditions, it will be seen that, in depressing the platen, sufficient energy must be exerted on the universal shaft 56 to overcome the gradually increasing tension of the already 20 tensioned strong springs 54, as well as the lesser gradually increasing tension of the counterbalancing spring 40.

25 Release of the universal shaft 56 enables the strong springs 54 operating upon the toggles 41, and the counterbalancing spring 40 operating through the fingers 38, separately from the springs 54, to restore the platen to elevated position.

30 As soon as the platen reaches its elevated position, the effect of the counterbalancing spring 40 becomes practically nil, but the strength of springs 54 is only slightly reduced, considerable tension remaining therein to press the platen firmly against the paper clamping bars 5.

35 It will be understood that the platen is not raised appreciably, past its counterbalancing position by the springs 54, the important function of which is to press the platen against the paper clamping bars with sufficient force to hold the 40 work in place, reduce the warpage, if any, in the platen, and produce a uniform clamping action.

45 The toggles 41 are connected to a universal cross-shaft 56, (Figures 4-7) journaled in ball bearings 57 in the frame side members 2, for simultaneous operation, as follows. The front and rear toggles 41 on the same side of the platen 4 have their long arms 43b connected by links 58 pivotally connected at 59 to the free ends of depending arms 60 fast on the shaft 56. Said shaft 50 56 is operatively connected by means of a depending arm 61 fast thereon and a draw link 62 to an operating crank 63 (Figures 1-4) pivoted at the rear of the frame 1 on a step bearing 64, and movable rearwardly to operate the shaft 56 and 55 toggles 41 in a platen-depressing direction. The operating crank 63 is provided with a stop arm 65, (Figures 1 and 2) adapted to contact the cross member 32 of the frame to limit its rearward movement, and hence the extent of depression 60 of the platen, and at its free end, the operating crank carries a vertical roller 66, the purpose of which will presently appear.

65 Mounted on the rear of the line space carriage 9 are selective means for establishing an operating connection between the carriage and crank 63 in timed relation to the return of the carriage to different positions. A frame or mounting 67 including vertical end brackets 68 (Figures 1-3 and 8-10) and horizontal upper and lower bars 69 and 70, respectively, is secured, as by bolts 71, to the end members 13 of the carriage 9.

70 A coupling device 72 is mounted upon the frame 67, including preferably, a horizontal push-bar 73 secured at one end to a vertical pintle 74 journaled at its opposite ends in the upper and lower bars

69 and 70, respectively, upon which the push bar may be swung from an inoperative position, parallel with said bars, (see Figures 1 and 2) to an operative position, at a right angle to the bars 69 and 70, to provide an extension member on the carriage 9 with its free end in line with the roller 66.

75 A bifurcated centering head 75 is provided on the free end of the push bar 73 and is adjustably retained thereon by a spring pressed dog 76 (Figures 1, 2 and 21) engaging, in the normal position of the parts, a notch 77 on the under side of said bar. The centering head 75 is rotatably adjustable on the bar 73 to an inclined position as in Figure 9, in which the dog 76 engages a second notch 78 when the head is located within the frame 67, as in Figures 1 and 2, to hold the dog in unobstructing position should it be desired to tilt the line space carriage upwardly on its rollers 14 for purposes such as repair.

20 The coupling device 72 is yieldingly retained in its operative and inoperative positions, respectively, by an overthrow preventing latching device 79 (Figures 1, 2, 8, 9 and 10) which may conveniently comprise a short crank arm 85 projecting radially from the pintle 74 at a point intermediate its ends, an angular link 83 being pivoted at one end, at 100, to the outer end of the crank arm 85, and having a tensioned spring 84 connected to its opposite end, the spring being anchored at 101 to the bracket 68, as shown in Figure 10. The elements are so arranged that by swinging the coupling device from one to the other of its positions, the pivot point 100 is shifted from one side to the other of a dead center 35 taken through the pintle 74 and the anchorage 101 of the spring 84.

30 As disclosed in Figure 10, in full lines, the coupling device is in its folded or idle position, the pivot point 100 lying far to the opposite side of the center of the pintle 74, due to the angular link, the angle of which embraces the pintle. In this position, the free end of the angular link at the point of connection of the spring 84 therewith, lies in line with the pivot point 100 but on the opposite side of the pintle therefrom, and in line with the spring anchorage 101, and the parts so arranged from a positive latch to hold the coupling device idle.

40 By swinging the coupling bar 73 clockwise to the position shown in dotted lines in Figure 10, the pivot point 100 is swung to the opposite side of its dead center, the coupling arm as it starts its clockwise travel, first disengaging the link 83 from the pintle, and as the pivot point 100 passes its dead center, the spring 84 is free to snap the coupling bar to its rearward, effective position.

45 A stop member 82 (Figures 8, 9 and 11) fast on the pintle 74, arrests the coupling bar 73 at either limit of its travel by contact with abutments 80 and 81, respectively, depending from the upper rod 69 of the frame.

50 A tie rod 102 extending between and connecting the pintle 74 and push bar 73, braces and affords strength and rigidity to the coupling device.

55 The push bar 73, when swung counter-clockwise (Figure 10) restores the overthrow preventing latch 83 and connected parts to the full line positions shown, the spring 84 operating to bring the parts to such positions as soon as the pivot point 100 passes the dead center.

60 The spring-urged link 83, by its engagement with the pintle 74, operates to arrest the coupling 75

device, and the abutment 81 merely prevents overthrow of the coupling device.

It will also be noted that, because of the overlapping arrangement of the latching device, the pivoted end of the link 83 has a greater travel than does the free end of the link.

The operation of this invention under the different conditions presented by the use of work sheets of different lengths, is as follows:

10 Assume that it is desired to write or enter amounts on a full length sheet or form.

The coupling device 72 is adjusted to inoperative position (Figure 1) and the carriage 9 is shifted rearwardly along the tracks 15 to its limit of travel either by hand or motor, leaving the writing area of the platen clear to receive and support the work sheet.

As the carriage approaches its limit of rearward travel, the lower bar 70 of the frame 61 20 contacts the roller 66 carried by the operating crank 63 and projecting upwardly into the path of such bar.

Continued rearward travel of the carriage to its limit of movement rocks the operating crank 63 25 and, through link 62, arm 61 and the universal shaft 56, (Figure 5) operates to simultaneously rock the longer arms 43b of the several toggles 41 to "break" or flex the latter, and positively draw the platen downwardly, against the tension of the counterbalancing means 38, 40.

The platen is thus withdrawn from the edge clamps 5 to enable the edges of the work sheet to extend therebeneath as the sheet is positioned on the platen.

35 Obviously, the weight of the carriage is sufficient to maintain the platen in its lowered position, against the tension of the toggle restoring springs 54 and the platen counterbalancing spring 40.

40 Coincident with the arrival of the printing carriage 9 at its rearward limit of travel, the trip lug 33 on the carriage wipes over the rearmost cam 32 on the motor control bail 25, rocking the bail back to its median position and shifting the

45 motor control shaft 21 to neutral position to interrupt the motor circuit (not shown) to the motor 29 and thus cut off the transmission of power to the drive for the carriage 9. Contact of the trip lug 33 with the shoulder on the rear-most cam 32 (Figure 1) arrests the printing carriage at its rearward limit of travel.

The work sheet having been positioned on the platen, the printing carriage 9 is advanced from its rearward limit of travel manually, or by rocking the motor control bail from its median position, in the opposite direction from which it was rocked when starting the rearward travel of the carriage, to bring the printing point of the carriage to the first writing line on the work sheet or form.

60 The carriage, on such advance, withdraws from the path of the roller 66, to free the platen elevating and counterbalancing mechanisms to the action of their springs, which restore the platen to printing position, and cause it to press the edges of the work sheet against the edge clamps 5 to hold the work in place.

Upon completion of the writing on the work sheet, the carriage 9 is returned to its rearward limit of travel, to lower the platen as heretofore explained, and permit the removal of the work sheet or form.

65 In recording upon short, for instance, half length sheets or forms, the coupling 72 is swung to operative position and the head 75 picks up

the roller 66 and depresses the platen coincidentally with return of the carriage 9 through the shorter return excursion sufficient to clear such work.

At a suitable point on the motor control bail 25, with relation to the return position of the carriage 9 when operating on short length sheets, a motor control cam 86 (Figures 3, 17, 18 and 19) is provided to disconnect the motor drive at the proper time and in the same manner as described with reference to the cams 32. The cam 86 is preferably hinged to the bail 25, as at 87, for swinging adjustment into or out of the path of movement of the lug 33. A leaf spring 88 projects through a slot 89 in the adjustable cam 86 10 to bear against flat portions 89' and 90 on the cam and yieldingly retain it in adjusted position.

15 Mounted on one side of the main frame 1 is a platen depressing key lever 91 (Figures 1 and 3) connected by a link 92 with a crank arm 93 20 fast on the universal shaft 56, and by means of which, the platen 4 may be manually depressed without returning the printing carriage to the rear, if desired.

25 It will be seen that the platen counterbalancing and moving mechanisms, respectively, are adapted for normally exerting forces at a series of points against the platen to provide for elevating the same uniformly that is to say maintaining it in horizontal position. Obviously this 30 provides for uniform clamping pressure along the edges of the work and obviates buckling of the work such as is liable to occur with non-uniform clamping pressures. Furthermore by virtue of the short and long arms 43a and 43b of 35 the toggles 41, connection of the former to the platen 4 and springs 54, and operation of the toggles 41 through the long arms 43b the platen operating mechanism is effective to impose forces, or leverage, to depress the platen in excess of 40 the elevating forces exerted by said moving mechanism. This facilitates overcoming the combined platen elevating forces and provides for easy carriage operation of said platen moving mechanism.

45 Ease of operation of the platen moving mechanism, in platen depressing operations is further facilitated by the relation of the points of connection of the spring 54 to the toggle 41 and frame 1. As will be clear these connections are 50 such that when the lever members 42 are rocked about their fulcrums 43, in a platen depressing direction, i. e. clockwise, as viewed in Figs. 4 and 5, the leverage of the short arms 43a progressively decreases, thus increasing the effectiveness of the long arms 43b and in direct ratio to the increasing resistance of the springs 54 and also of the spring 40 of the counterbalance mechanism. Consequently the platen operating mechanism is operative in said direction to apply 60 platen depressing forces gradually increasing in direct ratio to the increasing resistance exerted in a platen elevating direction.

55 By virtue of the advantages in leverage, described in the immediately preceding paragraphs, the platen operating mechanism is operative in a platen depressing direction, by the application thereto of a comparatively light substantially uniform force so that extra load on the carriage retracting motor is reduced to a minimum 70 degree.

65 In platen elevating operations the effective leverage of the short arms 43a progressively increases in direct ratio to the decrease in force exerted by the springs 40 and 54 so that the 75

elevating and clamping force applied is substantially uniform. The result is that the platen is engaged with the clamping bars 5 with a minimum of shock, and rebound and noise are practically eliminated.

The foregoing constitutes a detailed embodiment of a preferred form of my invention, but it is to be understood that right is herein reserved to such modifications thereof as fall within the scope of the protection prayed.

I claim:

1. In a machine of the class described, the combination with a platen movable toward and from the writing plane to clamp, and to release the work, respectively, and a travelling carriage, movable in line and letter spacing-directions relatively to the platen; of carriage-operated mechanism for moving the platen in one of its said directions of movement, and means for selectively controlling operation of said mechanism in timed relation to travel of the carriage to different positions.
2. In a machine of the class described, the combination with a vertically movable platen, and a travelling carriage, of platen-moving mechanism operative to depress the platen, and reacting to exert a lifting force thereagainst, and means for automatically operating said mechanism to depress the platen in timed relation to travel of the carriage to different positions, said means automatically stopping the carriage in said different positions.
3. In a machine of the class described, the combination with a frame, a carriage travelling thereon, and a vertically movable platen, of platen-operating mechanism, including selective devices on the frame and carriage, respectively, adapted for cooperation at different points in the travel of the carriage to move the platen.
4. In a machine of the class described, the combination with a frame, a carriage travelling thereon, a carriage-operating motor, and a movable platen, of platen-operating and motor-controlling mechanism, including selective devices on the frame and carriage, respectively, adapted for cooperation at different points in the travel of the carriage to move the platen, and to control the motor.
5. In a machine of the class described, the combination with a vertically movable, flat platen, and a travelling carriage, of platen-operating mechanism, including front and rear pairs of toggles operative simultaneously in platen-elevating and depressing directions, respectively, and locking against movement in a platen-elevating direction, means for tensioning the toggles against movement in one direction, and carriage-operated means for operating the toggles against the action of said tensioning means.
6. In a machine of the class described, the combination with work-clamping means, including a movable platen, and clamping members with which the platen coacts to clamp, and to release, the work; and a travelling carriage and printing mechanism, of platen-counterbalancing mechanism, normally exerting elevating forces at a series of points against the platen, platen-depressing mechanism operative to impose depressing forces upon said platen in excess of the elevating forces exerted by said counterbalancing mechanism, to overcome the combined elevating forces, and carriage-operated means for operating the platen-depressing mechanism, including an extension member on the carriage movable into and from effective and ineffective positions, respectively.
7. In a machine of the class described, the combination with work-clamping means, including a movable platen, and clamping members with which the platen coacts to clamp, and to release, the work; and a travelling carriage and printing mechanism, of platen-counterbalancing mechanism normally exerting elevating forces at a series of points against said platen, platen-depressing mechanism operative to impose depressing forces upon said platen in excess of the elevating forces exerted by said counterbalancing mechanism, carriage-operated means for operating the platen-depressing mechanism, including an extension member on the carriage movable to effective and ineffective positions, respectively, and a mechanism for yieldingly retaining said member in either of said positions.
8. In a machine of the class described, the combination with work-clamping means, including a bodily movable platen, and clamping members with which the platen co-acts to clamp, and to release, the work; a travelling carriage and printing mechanism, and platen-shifting mechanism; of carriage-operated mechanism effective upon the platen-shifting means, to shift the platen in one direction, such carriage-operated mechanism including an extension member on the carriage movable to effective and ineffective positions, respectively, and a latch mechanism for retaining said member in either of said positions.
9. In a machine of the class described, the combination with a track frame, a travelling carriage and printing mechanism on the frame, and work-clamping means, including a bodily movable platen, of carriage-operated platen-moving mechanism, including an element on the frame directly operated by the carriage in one position of the latter, an extension member on the carriage for operating said element in another position of the carriage, and movable to effective and ineffective positions, respectively, and a latch mechanism for retaining said member in either of said positions.
10. In a machine of the class described, the combination with work-clamping means, including a vertically movable platen, of counterbalancing mechanism exerting elevating leverage against the platen, and platen-depressing mechanism, including opposed pairs of tensioned toggle levers normally exerting elevating leverage at a series of points against the platen, and operative to impose platen-depressing leverage in excess of the elevating leverage exerted by said mechanism, to facilitate overcoming the combined platen elevating leverage, and means to simultaneously operate said levers.
11. In a machine of the class described, the combination with a frame, work-clamping means, including a vertically movable platen, and a travelling carriage and printing mechanism, of platen-depressing mechanism, including opposed pairs of tensioned toggle levers normally exerting elevating leverage at a series of points against the platen, and operative to impose depressing leverage against the platen in excess of said elevating leverage, a crank element on the frame, operating connections between the crank and said levers, and means for operating said crank by travel of the carriage, including an extension member on the carriage movable into and from cooperative relation to said crank.
12. In a machine of the class described, the combination with work-clamping means, including a bodily movable platen, and clamping mem-

- bers with which the platen co-acts to clamp, and to release, the work, a travelling carriage and printing mechanism, and platen-shifting mechanism; of carriage-operated mechanism effective upon the platen-shifting means to shift the platen in one direction, such carriage-operated mechanism including an extension member on the carriage movable to effective and ineffective positions, respectively.
10. 13. In a machine of the class described, the combination with a frame, a travelling carriage and printing mechanism on the frame, and work-clamping means, including a bodily movable platen, of carriage-operated platen-moving mechanism, including an element on the frame directly engaging the carriage in one position of the latter, and an extension member on the carriage for operating said element in another position of the carriage and movable to effective and ineffective positions, respectively.
15. 14. In a machine of the class described, the combination with a travelling carriage and printing mechanism, and work-clamping, including a movable platen, of platen-moving mechanism, including opposed pairs of toggle levers normally exerting elevating leverage at a series of points against the platen, and operative to depress the latter, and carriage-operated means for simultaneously operating said levers at selected points in the travel of the carriage.
20. 15. In a machine of the class described, the combination with a travelling carriage and printing mechanism, a carriage-propelling motor, and work-clamping means, including a bodily movable platen, of platen-moving mechanism, including opposed pairs of toggle levers, and carriage-operated means for simultaneously operating said levers and rendering the motor ineffective at selected points in the travel of the carriage.
25. 16. In a machine of the class described, the combination with work-clamping means, including a movable platen, of platen-elevating and depressing mechanism, including opposed pairs of toggle levers locking against platen-elevating movement in the fully elevated position of the platen, said levers being tensioned against platen-depressing movement, and operative to exert progressively increasing leverage in opposition to the tension exerted thereagainst, and means for simultaneously operating said levers.
30. 17. In a machine of the class described, the combination with work-clamping means, including a platen adapted for elevation and depression, of reactive counterbalance mechanism supporting less than the weight of the platen in the elevated position of the latter, and counterbalancing said platen in the depressed position thereof, and platen-operating mechanism reacting to elevate said platen, and exerting a progressively increasing leverage in a platen-elevating direction.
35. 18. In a machine of the class described, the combination with work-clamping means, including a platen adapted for elevation and depression, of reactive counter-balance mechanism supporting less than the weight of the platen in the elevated position of the latter, and counter-balancing said platen in the depressed position thereof, and platen-operating mechanism reacting to elevate said platen, and exerting progressively increasing leverage in platen-elevating and depressing directions, respectively.
40. 19. In a machine of the class described, the combination with a platen shiftable to its writing position and to its work-releasing position, respectively; and a carriage adapted to travel relatively to the platen; of means to support the platen in, and return it to, one of its positions; operating means connected with the platen-supporting means and extending into the path of travel of the carriage to be actuated thereby upon the approach of the carriage to one limit of its travel, to shift the platen to the other of its positions; and means operable by the carriage, and adjustable into and out of position to actuate the platen-operating means as the carriage approaches another limit of its travel.
45. 20. In a machine of the class described, the combination with a platen shiftable to its writing position and to its work-releasing position, respectively; and a carriage adapted to travel relatively to the platen; of means to support the platen in, and return it to, one of its positions; operating means connected with the platen-supporting means and extending into the path of travel of the carriage; and alternative means interposed between the carriage and the operating means to effect the actuation of the operating means at different points in the travel of the carriage, to shift the platen to the other of its positions.
50. 21. In a machine of the class described, the combination with a platen shiftable to its writing position and to its work-releasing position, respectively; and a carriage adapted to travel relatively to the platen; of means to support the platen in, and return it to, one of its positions; operating means connected with the platen-supporting means and extending into the path of travel of the carriage; and selective means interposed between the carriage and the operating means to effect the actuation of the operating means at different points in the travel of the carriage, to shift the platen to the other of its positions, one of the selective means adapted to become effective ahead of another of said selective means, in the traverse of the carriage.
55. 22. In a machine of the class described, the combination with work-clamping means, including a bodily movable platen; a travelling carriage and printing mechanism; and a carriage operating motor; of platen-counterbalancing mechanism; carriage-operated mechanism to move the platen; means to selectively control the operation of the carriage operated mechanism in timed relation to the travel of the carriage to different positions; and carriage-operated devices to control the operation of the motor in said different positions of the carriage.
60. 23. In a machine of the class described, the combination with a frame; a carriage travelling thereon; a platen mounted in the frame for elevation and depression; and clamping bars contacted by the side edges of the platen when elevated; of means to counter-balance the weight of the platen, including opposed levers, and a common resilient means connecting the levers to cause them to exert a lifting force near the front and rear edges of the platen along the median line thereof; operating means to depress and elevate the platen, including resilient members superior to the counterbalancing means and operable to exert a considerable pressure against the side edges of the platen to press the latter forcibly against the clamping bars; and carriage driven means to actuate the operating means to depress the platen.
